[57] CLAIM

The ornamental design for a vegetation blower apparatus, as shown and described.

DESCRIPTION

FIG. 1 is a front and left side perspective view of a vegetation blower apparatus showing our new design; FIG. 2 is a rear and left side perspective view thereof;

FIG. 3 is a left side view thereof;

FIG. 4 is a right side view thereof;

FIG. 5 is a top view thereof;

FIG. 6 is a bottom view thereof;

FIG. 7 is a front view thereof; and,

FIG. 8 is a rear view thereof.

It will be understood that the broken line shown throughout the drawings is for illustrative purposes only and forms no part of the subject invention.
